RAIL TREATMENT APPARATUS

Royal E. Frickey, San Francisco, and Arion S. Kalenborn, Redwood City, Calif., assignors to Welding Service, Inc., San Francisco, Calif., a corporation of California

Application May 18, 1932, Serial No. 612,066

17 Claims. (Cl. 266—6)

This invention relates generally to apparatus and methods for the treatment of railroad rails, to effect hardening of the same. It has particular application to the treatment of rail joints, 5 to harden the upper surfaces of the adjacent rail ends.

The hardening of railroad rails, where the rails have been laid, necessarily involves certain practical problems, particularly since the hardening must be carried out under field conditions. The apparatus employed must necessarily be portable, and it should be so economical in operation, as to enable treatment at a minimum of cost. Furthermore the apparatus and method 15 employed should be of such a character that uniformly good results can be secured with relatively unskilled workmen, such as are available for field work. In the past it has been proposed to harden rail ends by heating the same to a relatively high temperature of say 1500 deg. F. by an oxy-acetylene torch, followed by rapid chilling with water. Following chilling, a re-heating was necessary to secure a proper temper. Such methods have not met with universal approval, due among other reasons to lack of uniformity of the degree of hardness produced, and the skilled character of labor required.

We have found that superior results can be secured in the heat treatment of rails, if hardening is effected by the use of oil rather than water. The use of oil, in the method outlined herein, not only results in more uniform hardening for successive treatments, but also makes possible the omission of a separate and distinct reheating to effect tempering. However the use of oil involves distinct problems. For example because oil is relatively expensive compared to water, the quantity employed for each treatment cannot be wasted.

40 It is an object of the present invention to devise an apparatus and method for the hardening of rails, which will make possible successful operations on a commercial basis, and which will be well adapted for prevailing field conditions.

45 It is a further object of the invention to devise an apparatus and method of the above character which will make possible the use of oil as a liquid chilling medium, but which will conserve the oil utilized for each treatment.

50 A further object of the invention is to provide apparatus and method of the above character which will make possible uniformity of successive treatments, and which can be utilized with good results by relatively unskilled workmen.

55 Further objects of the invention will appear

from the following description in which the preferred embodiments of the invention have been set forth in detail in conjunction with the accompanying drawings. The appended claims are to be accorded a range of equivalents consistent with the state of the prior art. 5

Referring to the drawings:

Figure 1 is a diagrammatic view, illustrating apparatus incorporating the present invention.

Fig. 2 is a view similar to Fig. 1, illustrating 10 a modification in which certain functions are performed automatically.

Fig. 3 is a side elevational view, showing that part of our apparatus which is brought into position over a rail to be treated, to apply a liquid 15 chilling medium.

Fig. 4 is an end view of the apparatus as illustrated in Fig. 3.

Fig. 5 is an enlarged cross sectional detail, illustrating the lower portion of the apparatus illustrated in Figs. 3 and 4, applied to a rail joint 20 being treated.

Fig. 6 is a cross sectional detail taken along the line 6—6 of Fig. 5.

Fig. 7 is an enlarged cross sectional detail, 25 illustrating a possible modification of the apparatus illustrated in Figs. 3 to 6 inclusive.

Fig. 8 is a side view of the modification illustrated in Fig. 7.

Our method can be best understood after a 30 description of the apparatus illustrated in the drawings. That form of apparatus illustrated in Fig. 1 consists of a liquid reservoir 10, connected to outflow pipe lines 11, and an inflow pipe line 12. Reservoir 10 can be provided with external 35 heat insulation. Pipe lines 11 serve to deliver a liquid chilling medium to a structure designated generally at 13, which is adapted to be positioned upon a rail 14 at a rail joint. Valves 15 serve to control flow of liquid thru pipes 11. Suitable 40 forms for structure 13 will be presently described in detail, although it may be explained at this point that it preferably includes two open-bottomed containers 16 adapted to receive liquid from pipes 11, and which serve to bring the liquid into contact with limited areas of the upper surface of the rail.

In order to remove liquid introduced into receptacles 16, we have shown pipe lines 17 leading to the inflow sides of suitable liquid pumps 18. 45 Suitable check valves 19 are connected to the inflow ends of pipes 17. The outflow sides of pumps 18 are connected to a common pipe line 21, which leads to a suitable liquid cooler 22, such as a radiator adapted to transfer heat to an air 50 55

stream. Ventilation of radiator 22 is indicated by an air fan 23, driven by motor 24. The outflow side of radiator 22 connects with pipe line 12, leading back to reservoir 10.

5 As will be presently explained, it is desirable to maintain the temperature of oil in reservoir 10 at or about a constant temperature level, and this temperature level is made such as to be substantially higher than the highest temperature 10 of oil which may flow into the reservoir thru pipe 12. For this purpose we have shown a pipe line 26, connecting between pipe line 21 and reservoir 10. Flow of oil thru pipe line 26 is controlled by suitable means such as an electrical 15 solenoid or motor operated valve 27. Solenoid operated valve 27 is shown connected in series with an electrical actuating circuit 28, this circuit also including an electrical thermostat 29 which is in thermal contact with the liquid with- 20 in reservoir 10. In the event the temperature of liquid in reservoir 10 falls below a desired value, the contacts of electrical thermostat 29 are closed, to effect opening of solenoid valve 27, thus permitting direct flow of hot liquid from pipe 21 25 to reservoir 10. Pipe line 21 is shown provided with a throttling valve 31, which can be so adjusted that when solenoid valve 27 is open, liquid from pipe line 21 tends to flow directly to reservoir 10 in preference to flowing to the radiator 30 22.

In order to secure a thorough intermixing of the different temperatured liquids introduced into reservoir 10, we provide means such as indicated in Figure 1 which consists of an open-ended conduit 33 positioned intermediate the side walls of reservoir 10. Formed within conduit 33 there is a restricted throat 34, within which there is positioned a liquid impeller 36. Impeller 36 is shown mounted upon a rotatable shaft 37, adapted to be 40 driven by sprocket 38. Positioned within that end of reservoir 10 facing the outflow side of conduit 33, there is a semi-toroidal shaped wall 39. Upon rotating shaft 37, liquid within reservoir 10 is caused to repeatedly circulate through conduit 45 33, in the direction indicated by the arrows, to secure thorough intermixing. Direct heating of liquid in reservoir 10 can be effected by an electrical heating element 42, mounted upon and surrounding the outer periphery of conduit 33. This 50 electrical heating element is adapted to be connected to an external electrical circuit.

Motive means for driving pumps 18 has been represented by an electrical motor 43, having its shaft connected to pumps 18 thru suitable gearing 44. Electrical motor 43 is preferably of the adjustable or variable speed type, to enable an operator to adjust or vary the speed with which pumps 18 are driven. Motor 43 can also serve as a source of power for driving the sprocket 38 carried by shaft 37.

Operation of the apparatus illustrated in Figure 1, can best be explained after a description of a suitable structure 13 for positioning upon the rail to be treated. Such a structure has been illustrated in Figs. 3 to 6 inclusive and consists of a pair of open-bottomed receptacles or boxes 16a, which may be made substantially duplicates. Each receptacle consists of side walls 46, and walls 47 and 48, and a top wall 49. The lower 65 edges of the side and end walls are grooved as indicated at 51, to retain a packing 52 of suitable material, such as asbestos fibre. The contour presented by the lower edge of each receptacle 70 16a is such that packing 52 of each receptacle 75 seals about an area extending substantially en-

tirely across the upper surface of the rail 14, as shown in Fig. 6. The length of the area encompassed by packing 52 extends longitudinally of the rail, and where the end portions of rail sections at a rail joint are being treated, the areas extend in as close a proximity as possible to the adjacent end faces of the rail sections. These areas have been indicated in the drawings by letters A, and are obviously separated by any gap 53 which may exist between the adjacent end faces of the rail 10 sections.

While connecting means is provided between the receptacles 16a, this connection is preferably such as to permit individual alining and adjusting movements. Thus to afford a suitable form of articulate mechanical connection, we have shown a pair of spaced parallel guide channels 54 which are loosely engaged by lugs 56 formed on the upper edges of receptacle 16. Guide channels 54 are carried by a common head 57, which in turn is connected to the lower end of a depending tube 58, by a special support journal 59. Tube 58 forms a part of support means which will be presently described. The journal 59 illustrated in Figs. 5 and 6 consists of a pin 61, having its axis arranged generally longitudinally with respect to receptacles 16a, and having its ends slidably retained by parallel channels 60, which in turn are mounted upon head 57. The lower end of tube 58 is journaled upon pin 61, as by means of a ball bearing assembly 62. This type of journal means 25 59 permits guide channels 54 and thus receptacles 16a to be adjusted about a vertical axis symmetrical with respect to the two receptacles, and also to be rocked about a substantially horizontal axis laterally with respect to the length of the rail.

In order to cause receptacles 16a to aline themselves automatically, as they are lowered into position upon the rail, each receptacle is preferably 40 provided with side depending members 64 which are fixed to the side walls 46, and which are adapted to engage the side faces of the rail ball as shown in Fig. 6. Members 64 are preferably somewhat flexible, so that when in position as 45 shown in Fig. 6, they are sprung outwardly a slight amount without causing permanent deformation.

During a chilling operation, receptacles 16a are preferably urged downwardly with considerable 50 force upon the upper surface of the rail. In order to transmit such thrust between guide channels 54 and the receptacles, and at the same time permit limited movement of each receptacle about a transverse horizontal axis as accommodated by 55 the loose engagement between lugs 56 and channels 54, we have shown the guide channels 54 provided with depending members 66. The lower ends of members 66 are adapted to abut lugs 67 extending outwardly from the side walls of the 60 receptacles.

In order to afford an adjustment of the distance between the receptacles 16a in a direction longitudinally of the rail, we have shown a double-ended lever 68 having a pivotal connection with a lug 69 depending from one of the guide channels 54. A pair of links 71 serve to pivotally connect the ends of lever 68, with the adjacent side walls of receptacles 16a. Therefore by turning lever 68, receptacles 16a are forced 70 apart or moved together. The exact spacing between the receptacles can be fixed by means of a lever 72, having a pivotal connection with the side wall of one of the receptacles, as shown in Fig. 3. The free end of lever 72 is provided with 75

a pin, adapted to engage in any one of a series of apertures 13 formed in the side wall of the other receptacle.

To provide for an inflow of a liquid chilling medium into the receptacles 16a, we have shown the upper wall 49 of each receptacle provided with a suitable elbow 76, which in turn is connected to a flexible hose section 11a. Flexible hose section 11a corresponds to the pipe lines 11 of Fig. 1. To provide for the removal of liquid from each receptacle, the upper wall 49 of each receptacle is provided with an elbow 77, connected to a flexible hose section 17a. Hose sections 17a correspond to pipe lines 17 of Fig. 1. Communicating with the inner ends of elbows 77, are check valves 78 which have their inflow openings positioned in close proximity to the upper surface of the rail, when the receptacles are in normal operating position. Each receptacle is also preferably provided with a vent pipe 80, communicating thru its upper wall 49, and extending upwardly to the upper level of cooler 22.

The supporting means for the receptacles 16a and their associated parts, which have just been described, has been designated generally at 81 in Figs. 3 and 4. This supporting means in this particular instance consists of a depending structural channel 82, adapted to be carried by some suitable additional structure, such as a portable truck operating on the railroad track. Mounted upon the lower end of channel 82, there is a guide bearing 83 for slidably receiving the tube 58. Slidably fitted within tube 58 there is a plunger 84, which is normally urged toward retracted position by a compression spring 86. Fixed upon the upper end of tube 58, above bearing 83, there is a thrust collar 87. Below thrust collar 87, there is a pin 88, extending through and fixed to the upper end of plunger 84. Pin 88 is accommodated by slots 89 formed in the upper end of tube 58; so that limited movement is afforded between the plunger and tube 58. The upper end of plunger 84 is connected to a pair of toggle links 91 and 92. The upper end of link 92 is connected to channel 82 by the pivot pin 93. Links 91 and 92 are connected by pivot pin 94, and the lower end of link 91 is connected to the upper end of plunger 84, by pivot pin 96. Movement of links 91 and 92 past dead center position, in one direction, is limited by a stop 97, mounted upon channel 82. A tension spring 98 has its lower end connected to the upper end of plunger 84 and has its upper end anchored to channel 82. An operating lever 99 provided with a handle 101, is secured to link 91 in such a manner as to rotate together with the same.

Upon movement of lever 99 upwardly in a counter-clockwise direction as viewed in Fig. 3, it is evident that plunger 84 will first be raised a limited amount as permitted by slot 89, and then both plunger 84 together with tube 58 will be raised together thru guide bearing 83. After tube 58 and plunger 84 have been elevated a certain amount, they can be locked in such position, by means of a pin 103 being inserted in apertures 104 and 105, which at that time are aligned and are above guide bearing 83, to support the dependent assembly in nonoperative position. Apertures 104 and 105 are formed respectively in tube 58 and plunger 84. Conversely upon rotating lever 99 in a clockwise direction as viewed in Fig. 3, receptacles 16a are first lowered to a position in contact with the upper surface of the rail, while they are being guided by members 64. By further movement of lever 99 in a clockwise direction,

spring 86 is placed under compression to urge the receptacles downwardly with considerable force, and toggle links 91 and 92 cause lever 99 to be locked in its final position. Considerable downward force upon receptacles 16a is desirable in order to form an effective seal with the upper surfaces of the rail. General positioning of the receptacles, prior to lowering the same to final position, can be facilitated by a handle 107, which is shown mounted upon the head 57 (Fig. 6). 10

Now assuming that the apparatus of Figs. 3 to 6 inclusive is utilized for the structure 13 of Fig. 1, the operation and method to effect hardening of the end portions of rail sections at a rail joint, is as follows:—The end portions of 15 the rail sections at the joint to be treated, are first heated to a suitable elevated temperature, of say 1500 deg. F. In this operation it is preferable to apply heat to the upper surfaces of the rail ends, so that a layer of metal adjacent 20 these surfaces are heated to the required elevated temperature, without heating the entire depth of the rail to the same degree. Good results for example have been secured by rapidly playing a carbon arc over the upper surface of 25 the rail ball, until an upper layer of the rail ball has been heated to a sufficient degree. The amount of heating will depend upon the current density of the arc employed, the length of the arc, and upon the length of the heating op- 30 eration. These factors can be controlled to secure the desired degree of heating and to insure uniformity of results in successive treatments. Immediately after the heating operation, receptacles 16a are positioned directly above the 35 joint, with the center line of the joint alined with respect to the line of centers between receptacles 16a. The receptacles 16a are now lowered by turning lever 99 in a clockwise direction as viewed in Fig. 3, to bring the receptacles to rest 40 upon the heated ends of the rail sections. Further movement of lever 99 to its limiting position in a clockwise direction, sets toggle links 91 and 92 and causes spring 86 to force the receptacle 16a downwardly upon the rail. The pres- 45 sure thus applied to packing 52 affords a fairly liquid tight seal so that liquid to be subsequently introduced into the receptacles will be confined. Before lowering the receptacles to final position, the operator should so set lever 72 that the dis- 50 tance between the receptacles is at a minimum value consistent with the gap between the rail ends. In other words the receptacles should be as close together as possible, without interfering with sealing contact between packings 52 and the 55 upper end portions of the rail sections.

Assuming a final positioning of receptacles 16a, the operator now opens valves 15 and permits a liquid chilling medium to flow from reservoir 10 into both receptacles. It may be noted at 60 this point that the liquid chilling medium is preferably oil. As the streams of oil flow into the receptacles 16a, pools of oil immediately form upon areas A to effect rapid chilling of the same. Following introduction of oil into the receptacles, and after pools of oil have been formed upon areas A, operation of pumps 18 is commenced, to cause removal of hot oil thru check valves 78 and pipe line 21. Preferably the rate of removal is somewhat less than the rate of 70 introduction, so that as long as oil is being introduced from reservoir 10, pools of oil remain upon areas A. In the event the receptacles 16a become filled with oil, the oil will seek a hydrostatic level in vent pipes 80. After a predeter- 75

mined length of time, dependent upon the amount of heat which it is desired to transfer to the oil during the chilling operation, valves 15 are closed to interrupt further introduction of oil, but pumps 18 are continued in operation until all of the remaining oil has been removed from the receptacles. While the pumps 18 are in operation the oil removed from the receptacles, which is hotter than the oil flowing from reservoir 10, is circulated thru cooler 22, and the cooled oil from this radiator is reintroduced into reservoir 10 for reuse. Whenever during a series of successive treatments, the average temperature of the oil in reservoir 10 falls below a given value, which is preferably selected to be substantially higher than the temperature of cooled air being introduced by way of pipe line 12, electro-thermostat 29 causes the solenoid valve 27 to be opened, to permit direct introduction of hot oil from pipe line 21 to reservoir 10, until the average temperature of oil in this reservoir attains a predetermined maximum value, after which valve 29 is closed. By this automatic means the temperature of oil in reservoir 10 can be maintained adjacent a given value of say 140 deg. F.

If the apparatus has not been in operation for a relatively long period, the temperature of oil in reservoir 10 may drop down below the value desired. In this event, before a treatment is commenced, the oil in reservoir 10 can be heated up to a desired temperature, by applying current to the heating element 42.

During the chilling operation a certain amount of the oil will be vaporized, particularly during the initial contact of the oil with the hot rail surface, such vapor can discharge from the receptacles thru the vent pipes 80.

The chilling produced by our method is dependent upon the rate with which heat is abstracted by the oil, and upon the time period of the chilling operation. In order to secure uniformity of the hardening effect in successive operations, we prefer, particularly where the rail is made of special alloys such as high manganese rail steel, to so control the heating operation as to secure uniformity of heating in successive operations, and to so control the chilling as to secure a desired predetermined degree of hardness. With the apparatus of Fig. 1, the rate of removal of heat by the oil can be regulated by adjusting the speed of motor 43, and be maintaining the temperature of oil in reservoir 10 at a fairly constant level. Likewise the length of the period of treatment can be controlled by the opening and closing of valves 15.

Following the treatment of a particular joint, receptacles 16a can be lifted free of the rail by rotating lever 99 in a counterclockwise direction, and the apparatus moved to another joint, which in the meantime has been heated for a chilling operation. At the end of a chilling operation a layer of metal immediately adjacent areas A has been chilled to a mean temperature below the temperature of the adjacent heated portions of the rail. Therefore a flow of heat immediately occurs back into the chilled area, to cause a tempering or drawing effect. It has been found that with our method, which involves controlled chilling by the use of oil, and which localizes the chilling effect to the area to be hardened, no reheating of the rail ends to effect tempering is required. Obviously the absence of such a reheating treat-

ment is a material saving, not only in the amount of heat required, but also in time and labor involved.

A modification of the apparatus of Fig. 1 is illustrated in Fig. 2, in which certain functions are performed automatically after the apparatus is initiated into operation. In this case we employ an electrical timing motor 111, the speed of which can be adjusted, but which when once adjusted will operate at a substantially constant speed irrespective of variations in applied potential. Associated with motor 111, we provide electrical timing means, as representative of which we have shown a plurality of cams 112, 113, and 114, connected to a common shaft, and having a drive connection with motor 111 thru gearing 116. Pivoted levers 117, 118, and 119, are associated with cams 112, 113, and 114 respectively, and these levers carry mercury contactors 122, 123 and 124. Contactor 122 is connected in series with the current supply circuit 126 for motor 43. Valves 15a, corresponding to valves 15 of Fig. 1, are solenoid operated, and the electrical energizing circuit 127 for the same is controlled by contactor 123. Contactor 124 is connected in series with the energizing circuit 128 for timing motor 111. It is therefore evident that opening and closing of contactor 122 control starting and stopping of motor 43 and thus starting and stopping of pumps 18; opening and closing of contactor 123 controls opening and closing of the solenoid operated valves 15a; and opening and closing of contactor 124 controls the operation of timing motor 111. Manual switches 131 and 132, are shown connected in shunt with contactors 123 and 124.

The conformation of cams 112 to 114 inclusive is such that at the end of each complete revolution of the cams, lever 119 is caused to swing in a direction to effect opening of contactor 124, and thus cause deenergization of timing motor 111. To start the timing motor in operation it is necessary to temporarily close the switch 132. Likewise the contour of cams 112 and 113 is such as to cause levers 117 and 118 to swing, to effect opening and closing of contactors 122 and 123. At the beginning of a cycle of operation, contactors 122, 123, and 124 are open, and circuits 126, 127 and 128 are deenergized. A cycle of operations is started by temporarily closing switches 131 and 132, thus energizing and opening valves 15a and also energizing and starting timing motor 111. Switches 123 and 124 may be opened as soon as cams 113 and 114 have turned sufficiently to close contactors 123 and 124, respectively. A predetermined time interval after opening of solenoid valves 15a, contactor 122 is also closed to energize motor 43 and thus operate pumps 18. After solenoid valves 15a have been opened for a predetermined length of time, they are closed by opening of contactor 123 and after a predetermined length of time following closing of valves 15a, contactor 122 is opened to arrest operation of pumps 18. The cycle of movement is then completed by opening of contactor 124, to deenergize timing motor 111. Obviously the timing of the various functions and the timing of the complete cycle of movement, can be adjusted by varying the speed of timing motor 111. Likewise if desired the contour of cams 112 to 114 inclusive can be changed.

In Figs. 7 and 8 there is shown a liquid receiving receptacle so constructed that it can be readily modified to fit rails of varying sizes. Thus in this case the lower portion of each liquid re-

ceiving receptacle 16b is formed of a separate and replaceable shoe 136. A packing 137 made of suitable material such as asbestos fibre, is interposed between the upper edge of shoe 136, and 5 the lower edge of the main body of receptacle 16b. The opposed surfaces with which packing 137 engages, can be grooved to facilitate making a proper seal. The lower edge of shoe 136 is likewise grooved, and is provided with a suitable packing 10 138 adapted to seal upon the upper surface of the rail. Since 136 is attached to the main body of receptacle 16b, by suitable means, such as resilient clips 139. To retain the packings 137 and 138 in proper position, the inner and outer 15 faces of shoe 136 are shown provided with grooves 141, within which a thin wire 142 is wrapped. Wire 142 is wrapped over the packings 137 and 138, but is of sufficient fineness as to not interfere with proper sealing.

20 It is evident that with the construction of Figs. 7 and 8, the apparatus can be readily modified for operation upon rails of different sizes, merely by replacing shoes 136 with other shoes of a proper size consistent with the size of the rail 25 to be treated.

It is evident that further modifications may be employed other than those described, within the spirit of the invention. For example in place of using two receptacles 16a, a single receptacle can 30 be employed, provided suitable provision is made for preventing escape of oil thru the gaps between the ends of the rail sections. However we prefer to employ two receptacles, in order to facilitate proper sealing with the rail under varying 35 conditions. Likewise while recirculation of oil is desirable, it is possible to merely employ the receptacles 16a, or some simplified substitute structure which will confine the oil to a sufficient degree, without recirculating means. In such event the oil can be poured into the structure 40 manually to form an oil pool upon the heated rail surface, and then discarded after the chilling operation, or removed to a point of storage for reuse.

45 We claim:

1. In apparatus for the hardening of heated rail ends at a rail joint, a structure adapted to be positioned upon the end portions of adjacent rail sections at said joint, said structure comprising two open-bottomed receptacles, and means forming an articulate connection between said receptacles.

50 2. In apparatus for the hardening of heated rail ends at a rail joint, a structure adapted to be positioned upon the end portions of adjacent rail sections at said joint, said structure comprising two open-bottomed receptacles, means serving to seal the lower portions of said receptacles with respect to the upper surfaces of the rail sections, and means forming an articulate connection between said receptacles.

55 3. In apparatus for the hardening of heated rail ends at a rail joint, a structure adapted to be positioned upon the end portions of adjacent rail sections at said joint, said structure comprising two open-bottomed receptacles, means serving to seal the lower portions of said receptacles with respect to the upper surfaces of the rail sections, and means forming an adjustable connection between said receptacles.

60 4. In apparatus for the hardening of heated rail ends at a rail joint, a structure adapted to be positioned upon the end portions of adjacent rail sections at said joint, said structure comprising two open-bottomed receptacles, means serving to

seal the lower edges of said receptacles with respect to the upper surfaces of the rail sections, and means serving to connect said receptacles, said last named means permitting independent alignment of each receptacle in a direction lateral 5 with respect to the rail.

5. In apparatus for the hardening of heated rails, means forming an open-bottomed receptacle, and means serving to seal the lower edges of said receptacle with respect to the upper surface of the rail, said first means having a passage 10 serving to permit outflow of a chilling liquid introduced into the same.

6. In apparatus for the hardening of heated rails, means forming an open-bottomed receptacle, means for sealing the lower portion of the receptacle with respect to the rail, whereby the upper surface of the rail is exposed to a chilling liquid introduced into the receptacle, and means for continually removing liquid from the receptacle for reuse.

7. In apparatus for the hardening of heated rails, means forming an open-bottomed liquid receiving receptacle adapted to be positioned upon the rail, means for sealing the lower portion of said receptacle with respect to the rail, whereby the upper surface of the rail is exposed to a chilling liquid introduced into the receptacle, means for introducing a chilling liquid into said receptacle, and means for removing said 30 liquid from the receptacle and for returning the same to the point of introduction.

8. In apparatus for the hardening of heated rails, means forming an open-bottomed receptacle adapted to be positioned upon the rail, 35 means serving to seal the lower portion of said receptacle with respect to the rail, whereby a limited area of the upper surface of the rail is exposed to a chilling liquid introduced into the receptacle, means serving to introduce a stream of chilling liquid into the receptacle, means serving to remove chilling liquid introduced into the receptacle and for returning the same to said point of introduction, and means serving to cool said chilling liquid before reintroduction into said receptacle.

40 9. In apparatus for the hardening of heated rails, a reservoir adapted to contain a chilling liquid, a pipe connected to said reservoir serving to convey liquid from the same into contact with a heated surface of the rail, means for receiving liquid thus contacted with the rail, pump means for returning the liquid from said receiving means back to said reservoir, valve means for controlling flow of liquid thru said pipe, and means serving to effect opening of said valve 50 means at a predetermined time interval prior to actuation of said pump.

45 10. In apparatus for the hardening of heated rails, a reservoir adapted to contain a chilling liquid, a pipe serving to convey liquid from said reservoir and for returning the liquid from said reservoir into contact with a heated surface of the rail, means for receiving liquid from said receiving means back to said reservoir, a valve 60 serving to control flow of liquid thru said pipe, and means serving to effect actuation of said pump after a predetermined time interval following opening of said valve, and to effect closing of said valve prior to rendering said pump inoperative.

55 11. In apparatus for the hardening of heated rail sections at a rail joint, a pair of open-bottomed receptacles, means serving to seal the lower edges of said receptacles with respect to 75

the upper surfaces of the rail sections, means forming an articulate connection between said receptacles, and means carried by said receptacles, and adapted to engage the sides of the rail ball, to effect proper alining of the receptacles with respect to the rail.

12. In apparatus for the hardening of heated rail ends at a rail joint, open-bottomed liquid-receiving means adapted to be positioned upon the end portions of adjacent rail sections at a rail joint, and means serving to seal said first-named means with respect to the upper surface of the rail and also with respect to the gap between the rail ends, whereby liquid introduced into said first-named means is contacted with the upper surfaces of both said rail ends.

13. In apparatus for the hardening of heated rail ends at a rail joint, liquid-receiving means adapted to be positioned upon the rail at a rail joint, and means serving to seal said first-named means with respect to the rail and with respect to the gap between the rail ends, said seal being about a limited area of the rail's surface, and said first-named means being formed to permit liquid introduced into the same to contact with said limited area of the rail's surface and also being ported to permit outflow of liquid introduced into the same.

14. In apparatus for the hardening of heated rails, means forming an open-bottomed liquid-receiving receptacle, means serving to seal the lower edges of said receptacle with respect to the upper surface of the rail, whereby liquid introduced into said receptacle is contacted with a limited area of the rail's surface, and means carried by said first-named means to position the receptacle with respect to the rail.

15. In apparatus for the hardening of heated rails, a reservoir adapted to contain a chilling liquid, valve controlled means serving to convey liquid from the reservoir into contact with the surface of a heated rail, means for receiving liquid thus contacted with the rail, pump means for returning liquid from said receiving means back to said reservoir, and timing means for automatically controlling closing of said valve controlled means and operation of said pump means. 5

16. In apparatus for the hardening of heated rails, a reservoir adapted to contain a chilling liquid, valve controlled means serving to convey liquid from the reservoir into contact with the surface of a heated rail, means for receiving liquid thus contacted with the rail, pump means for returning liquid from said receiving means back to said reservoir, and timing means for automatically controlling closing of said valve controlled means and operation of said pump means, said timing means serving to close said valve means to interrupt further supply of liquid to the rail prior to effecting cessation of the pumping action. 15

17. In apparatus for the hardening of heated rails, means forming an open-bottomed liquid-receiving receptacle adapted to overlie a rail, said receptacle having an opening for introducing a chilling liquid into the same, and means for sealing the lower edges of said receptacle with respect to the rail head whereby liquid introduced into the receptacle is contacted with a limited upper portion of the rail's surface. 20 25
